US0D1043238S

(12) **United States Design Patent** (10) Patent No.: **US D1,043,238 S**
(45) Date of Patent: ** Sep. 24, 2024

(54) **LID FOR BEVERAGE CONTAINER**

(71) Applicant: **ENI-JR286, Inc.**, Torrance, CA (US)

(72) Inventors: **Jesse C. P. Lee**, Torrance, CA (US);
George A. Patrikeyev, Santa Cruz, CA (US)

(73) Assignee: **ENI-JR286, Inc.**, Torrance, CA (US)

(**) Term: **15 Years**

(21) Appl. No.: **29/904,882**

(22) Filed: **Oct. 12, 2023**

Related U.S. Application Data

(62) Division of application No. 29/814,861, filed on Nov. 9, 2021, now Pat. No. Des. 1,007,230.

(51) LOC (14) Cl. **07-01**

(52) U.S. Cl.

USPC **D7/392.1**; D7/396.2

(57) CLAIM

The ornamental design for a lid for beverage container, as shown and described.

DESCRIPTION

FIG. 1 is a top perspective view of a lid for beverage container, showing our new design.

FIG. 2 is a bottom perspective view thereof.

FIG. 3 is a front elevational view thereof.

FIG. 4 is a left side elevational view thereof.

FIG. 5 is a right side elevational view thereof.

FIG. 6 is a rear elevational view thereof.

FIG. 7 is a top plan view thereof; and,

FIG. 8 is a bottom plan view thereof.

The broken lines depict portions of the lid for beverage container that form no part of the claimed design.

1 Claim, 8 Drawing Sheets
